[57] **ABSTRACT**

In combination, a metal sheathing of a building, a plastic covering sheet, means for properly attaching said plastic sheet to said metal sheathing comprising a metal clip having a top portion folded over the top of said plastic sheet and having a laterally punched out portion extending through said plastic sheet, a weld pin having one end extending through punched out portion of said metal clip, to contact with metal sheathing.

1 Claim, 2 Drawing Sheets

FIG. 1

FIG. 2

FIG. 3

FIG. 4

1

**APPARATUS AND METHOD FOR
ATTACHING PLASTIC SIDING OR TRIM
PIECES TO METAL SHEATHING**

BACKGROUND OF THE INVENTION

No satisfactory method is known to properly attach plastic siding or trim pieces to metal sheathing of a building without burning the plastic siding or trim.

SUMMARY OF THE INVENTION

The present invention relates to overcoming the above-mentioned problem by pin or stud welding the plastic siding or trim pieces to the metal sheathing with a burn shield to prevent burning the plastic siding or trim.

BRIEF DESCRIPTION OF THE DRAWING

FIG. 1 is a front view of a burn shield embodying the present invention;

FIG. 2 is a side view thereof; and

FIG. 3 is a sectional view thereof;

FIG. 4 is an enlarged sectional view thereof taken along line 3—3 of FIG. 1 as applied to a plastic J channel and metal sheathing shown in dash lines.

FIG. 5 is front view of the burn shield as applied to welding a plastic siding to a metal sheathing; and

FIG. 6 is a vertical cross section taken along line 6—6 of FIG. 5.

**DESCRIPTION OF THE PREFERRED
EMBODIMENT**

FIGS. 1 2, and 3 show a burn shield embodying the present invention comprising a metal clip 1 bent to fold over the top of a plastic J channel 5, as shown in FIG. 4, or to a

2

plastic building siding 2, instead, as shown in FIGS. 5 and 6. The metal clip 2 has laterally punched out portions 1a and 1b which project through the plastic J channel 5, as shown in FIG. 4, or through plastic building siding 2, as shown in FIG. 6 to form a welded joint.

As shown in FIGS. 5 and 6, the welded joint is formed by a weld pin 1d to which a capacitor discharge welder is applied to create weld fastening to the metal sheathing without burning either the plastic J channel (or siding) 5, such as vinyl siding of FIG. 6 which burning would otherwise occur, disfiguring the plastic material.

The metal clip 1 in FIG. 1 shields the back of the siding. Its parts 1a and 1b protrude through the siding and shield the edges of the slot.

The invention may be a tab, as shown in FIG. 1, or a continuous piece extending throughout the entire length of the siding 2. The tabs shown in FIG. 1 could be applied in the field. The continuous piece could be done by the manufacturer.

The burn shield can also be used as a spacer for screw fastening the siding to the sheathing.

The screw placed through the flanges fastens the siding and allows movement for expansion and contraction.

I claim:

1. In combination, a metal sheathing of a building, a plastic covering sheet, and means for properly attaching said plastic sheet to said metal sheathing, the attaching means comprising a metal clip having a top portion folded over the top of said plastic sheet and having a laterally punched out portion extending through said plastic sheet, and a weld pin having one end extending through said punched out portion of said metal clip, to contact the metal sheathing.
